[57] CLAIM

The ornamental design for a reducer cap for a safety trocar, as shown and described.

DESCRIPTION

FIG. 1 is a bottom perspective view of a reducer cap for a safety trocar showing our new design;
FIG. 2 is a top perspective view thereof;
FIG. 3 is a front elevational view thereof, the rear elevational view being identical thereto;
FIG. 4 is a bottom plan view thereof;
FIG. 5 is a left side elevational view thereof, the right side elevational view being identical thereto;
FIG. 6 is a top plan view thereof; and,
FIG. 7 is a perspective view thereof, the broken line showing of the surgical trocar is for illustrative purposes only and forms no part of the claimed design.
